UNITED STATES PATENT OFFICE.

AUSTEN H. FOX, OF NEW YORK, AND ARNOLD W. LENDEROTH, OF STAPLETON, NEW YORK.

MAGNETIC CONTROLLING DEVICE FOR RAILWAYS.

1,298,029.

Specification of Letters Patent. Patented Mar. 25, 1919.

Application filed April 30, 1915. Serial No. 24,881.

To all whom it may concern:

Be it known that we, AUSTEN H. FOX and ARNOLD W. LENDEROTH, both citizens of the United States, residing at, respectively, 5 New York, county and State of New York, and Stapleton, county of Richmond, and State of New York, have invented certain new and useful Improvements in Magnetic Controlling Devices for Railways, of which 10 the following is a full, clear, and exact description.

The invention upon which is based the present application for Letters Patent, pertains to the general class of railway signaling or controlling devices, and is an improvement in the class of apparatus heretofore set forth and described in patents granted to Austen H. Fox No. 1,088,814 and to Fox and Lenderoth No. 1,007,192. 15 20 More specifically stated, the improvement resides chiefly in the electromagnetic structure adapted to be mounted on, or carried by, a movable vehicle or unit, and designed to be influenced by an armature, either comprising or co-extensive with the rail or rails of the track, and to be operated by properly constructed and located interruptions in the magnetic continuity of said armature, although the invention as a whole includes 25 other features or details, as will hereinafter more fully appear.

The new electromagnet devised for this purpose is one having a core supported in a vertical position above the track or a continuous armature and carrying at its lower end two elements or feet, movable one with respect to the other in the plane of the track, which, being of the same magnetic polarity, would be normally repelled one by the other 35 40 and separated, but which are both attracted by the rail or armature and held normally in close relation.

The movable element or elements of the magnet are caused to control electric circuits, which contain any suitable devices 45 for indicating the operation of such magnet or magnets, or for rendering their movement or operation effective for any other desired purposes, such as speed control, or 50 the like, so that by the installation along the

right of way of properly designed means for operating the movable elements of the magnets, any desired signal or indication may be given or withheld from the operative in control of the vehicle, or any other similar 55 result may be secured, by means of devices more simple in construction and certain in operation than any that have heretofore been used for such purposes.

The nature and purpose of the invention 60 will be better understood from the detailed description of the apparatus illustrated in the accompanying drawing, to which reference will now be made.

Figure 1 is a side view in elevation of the 65 electro-magnet attached to a car truck and showing a section of the co-operating rail or armature.

Fig. 2 is an end view of the same, showing the rail in section. 70

Fig. 3 is a section of the rail showing a modification of the monitor or controlling devices associated therewith.

Fig. 4 is a top plan view of Fig. 1.

Fig. 5 is a diagrammatic illustration of 75 circuit connections and devices in connection with a series of magnetic cores associated with the track.

Fig. 6 is an enlarged part sectional and side view of the detector magnet. 80

Fig. 7 is a central cross section of the same.

Fig. 8 is a top plan view of Fig. 6.

Fig. 9 is an enlarged view in perspective of one of the movable magnet elements, and 85

Fig. 10 is a diagram of circuit connections.

In the description which follows like numerals of reference are used to designate similar parts in all of these figures. 90

In Fig. 1 the numeral 1 indicates an iron or steel car wheel mounted in a journal bearing 2 carrying or supporting the end of the equalizing bar 3. Near the end of the latter is secured, in any proper manner, either permanently or otherwise, an arm 4, to which is joined, as by nuts 5, the vertical core of an electromagnet 6. This core is bent at right angles, as shown in Fig. 2, to form an axis on which is supported the 100

metal case or housing 17 for the movable elements of the magnet.

In the form of device herein shown, each of said elements is composed of a magnetic foot or depending portion 7, having a bearing 8 by means of which it is pivotally mounted on, or supported by, the right angle extension of the core 6 and movable thereon in the plane of the tracks, and a non-magnetic counterpoise 9 normally tending to balance the foot in any position which it may occupy with reference to the vertical line passing through its support.

The bearings for the two feet 7 are non-magnetic and anti-frictional in character, shown as composed of balls 10 in suitable run-ways, and each foot is preferably, although not necessarily, provided with a toe, or what is known as a "kicker" 11 extending across the path traversed by the foot.

To each counterpoise 9 there is secured, but insulated therefrom, a metal plate 12, the upper edge of which extends up between pairs of contact points, of which three sets 13, 14 and 15 are here shown, secured to an insulating support in the housing 17. By the use of two contacts between which the plate 12 moves, the objectionable effects of vibration are entirely avoided and the circuit permanently closed through the contacts when engaged by the metal portions of the plate 12. The plates 12 contain inserts 16 of insulating material; one of which lies between the points 15 when the feet are held in close relation by the attraction of the armature or rail, and the other of which comes between points 13 when, on the absence or cessation of such attraction, the feet are repelled and separated. The relations of these parts is such that the contacts are broken for a certain period during the passage of a foot from one position to the other.

Immediately under the antifrictional bearing 8 is a fixed stop 18, which lies between projections 19, on the movable elements 7, and limits the movements of these elements in opposite directions. That is to say, when the feet are attracted by the rail, their inner projections 19 are held against this stop 18, but when the attraction ceases, the two feet swing apart until the outer projections 19 are arrested by the stop 18.

For the operation of the electromagnet, sections of track are provided at the desired or proper points which are non-magnetic. For example, the carbon steel rails may be replaced by a section of predetermined length of manganese steel rail 20, so that when the magnet passes over such section its feet become separated by their own magnetic repulsion.

It may often become necessary or desirable, however, to cut out the non-magnetic effect of a manganese steel section to a

greater or less extent, and this may be accomplished in various ways. For example, an iron or steel bar or T-iron 21 may be provided with means for throwing it up into a position alongside the head of the manganese rail where it will exert an attractive effect on the movable parts of the magnetic core, as indicated in Fig. 2. Or, in lieu of the magnetic bar, a series of electromagnetic cores 22 may be placed along side one or both sides of the non-magnetic section and included in the circuit of a source of current 23 and adapted to be magnetically controlled by any form of switch or relay 24, as shown in Figs. 1, 3 and 5.

When these magnetic cores are used they are placed at such distances apart that the feet 7, whether the vehicle is in motion or at rest, are attracted by them in such manner as to be retained in their close relation to one another.

In the practical applications of the invention one of the above described magnetic devices is used on each side of the vehicle and is supported in such relation to the track 90 and to one of the car wheels that the latter forms a path for the magnetic lines developed by the core and passing from one to the other pole of the same. In this way the efficiency of the magnet is very greatly increased.

The primary and most important object of the invention above described, is to take advantage of the fact that a movable magnetic element requires a given time to move 100 under magnetic influence from one position to another, and that the track can be so arranged as to represent a magnetic effect of given length, either by means of a path composed of a magnetic substance, or by the creation of a magnetic field of given length along the right of way. The length of time of the presentation of this magnetic influence may depend upon and be varied by the speed of the vehicle on which the primary magnetic member is located, and the time must be sufficient to permit the member to move from a given position against the resistance to motion due to the inertia of its parts while the magnetic effect is being exerted.

By the movements of the magnetic members between their two positions of attraction and repulsion, any desired effects may be produced, as for example, the lighting 120 of two lamps or sets of lamps, as may be understood by reference to Fig. 10. In this figure the pairs of contacts represented by the numerals 13, 14 and 15, are connected up with a source of current 25 and with 125 groups of lamps 26 and 27. Examining this figure in connection with Fig. 6, it will be seen that when the plates 12 are in the position maintained by an attractive effect of the armature members, the portions of the 130

circuit 28 and 29 are connected through the battery and lamps 26, but that when the armature members are repelled, the lamps 27 are brought into circuit with the source and portions of the circuit 29 and 30.

The external track conditions are thus indicated on the moving unit, and these can be so arranged as to require certain fixed periods of time to elapse in order to effect 10 their manifestation.

The absence altogether of these magnetic influences, it will be seen, will result in a given manifestation on the moving unit. The presence or return of the influence, say, 15 by the positioning of a T-iron alongside the outside head of the rail, will produce an effect on the outside or by-pass foot 7 and return it from a repelled to an attracted position.

It will thus be seen that it is only necessary to the attainment of a given result that the magnetic effect be present long enough to overcome the inertia of the by-pass foot, and this means duration of magnetic effect 20 along the right of way for a sufficient distance to enable it to be effected at the highest rate of speed. This condition will exist in actual practice whenever a clear indication is to be transmitted to the moving unit, and represents the additional length of magnetic 25 effect which is under the control of the signals over the permanent effect at each point established to represent the safe speed when these signals are set at "stop." This amount 30 of permanent effect will be a permanent magnetic path, the additional effect being either a movable magnetic path or a series 35 of magnets or magnet coils.

Where no speed is permitted when signals that control the relay 24, for example, 40 are set at "stop", then the external magnetic effect is entirely removed and only presented when the clear condition exists.

For energizing the detector magnet there 45 may be employed a battery 31, or other suitable source of current, in a circuit which is constantly closed, and which will give some signal or indication of its failure to act, or of its grounding.

The movable pole elements may be designed to all have the same time element in 50 operation, related as may be necessary to the working conditions, and the device may be used for many purposes and in many ways, 55 either singly or collectively, and in various operative relations which need not be further explained herein, as the principles of such operation have been fully set forth in the patents above referred to.

The advantages of the device, constructively and operatively considered, are believed to be sufficiently apparent to call for 60 no more detailed explanation or description.

What we claim is:

65 1. A detector magnet for systems of rail-

way signaling or control, adapted to be carried by a moving vehicle in proximity to an extended armature, comprising a magnetic core bent at right angles to form a bearing for two magnetic elements movable 70 in the plane of the track, and which, being of like magnetic polarity, are repelled and forced apart, but by the attraction thereon of the armature are drawn into close relation.

2. A detector magnet for systems of rail- 75 way signaling or control, adapted to be carried by a moving vehicle in proximity to an extended armature, comprising a magnetic core pivotally supporting two magnetic elements movable in the plane of the track 80 and having non-magnetic counterpoises, the said elements being of like magnetic polarity whereby they are repelled and forced apart by magnetic repulsion, but by the attraction therefor of the armature they are 85 drawn into close relation.

3. A detector magnet for systems of rail- 90 way signaling or control adapted to be carried by a moving vehicle in proximity to an extended armature, comprising a mag- 95 netic core, two magnetic elements movable thereon which, by being of the same polarity, are repelled and forced apart, but which, by the attraction of the armature, are drawn into close relation, electric circuit controllers operated by the movable elements and adapted to be opened and closed by the movements of the same, due to breaks in the magnetic continuity of the armature.

4. The detector magnet herein described, 100 comprising a magnetic core carried by a vehicle in proximity to the track, two magnetic feet pivotally mounted thereon by anti-frictional bearings and movable in the plane of the track, counterpoises connected 105 with the feet, circuit controlling plates carried by the counterpoises and contacts in engagement with which the said plates are adapted to move.

5. The detector magnet herein described, 110 comprising a magnetic core carried by a vehicle in proximity to the track, two counterpoised magnetic elements pivotally supported on said core and movable in the plane of the track, stops for limiting the 115 movements imparted to said elements by repulsion between them and by the attraction of the rail for them, and circuit controllers operated by the movements of said elements.

6. In a railway signaling or control sys- 120 tem, the combination with a moving vehicle, of a movable magnetic element having by reason of the inertia of its parts a constant time action in response to a given attractive forces, of a magnetic armature element made 125 of definite length corresponding to the time required by the movable magnetic element to act, and adapted to be positioned along the track in operative relation to said magnetic element.

7. In a railway signaling or control system, the combination with a moving vehicle, of a circuit controlling device comprising a magnetic coil and a movable core requiring for its operative movement a definite time under a given attractive force, and an armature composed of carbon steel rails hav-

ing interruptions in its magnetic continuity along the right of way in operative relation to the movable core.

In testimony whereof we affix our signatures.

AUSTEN H. FOX.

ARNOLD W. LENDEROTH.
